LOCK

Charles Ledin and Karl A. Brauning, Stamford, Conn., assignors to The Yale & Towne Manufacturing Company, Stamford, Conn.

Application March 6, 1931, Serial No. 520,575

5 Claims. (Cl. 70—14)

This invention relates to rim locks of the type in which the bolt mechanism is utilized to interlock the strike and the main casing of the lock.

In a commercial lock of this type, it is customary to use a pair of bolts moving in a substantially vertical direction and having actuating means for holding those bolts in a lower locking position or an upper unlocking position, and for deadlocking the bolts in those particular positions. It is the object of our invention to devise a mechanism by which we will accomplish all the various results necessary in a lock of this type in a very cheap and economical manner, in order that such a lock may be a commercially desirable article. Whereas, in the prior art, there are numerous locks of this particular type, and patents covering the same, very few of these locks have ever become commercially successful due to their poor internal construction, or due to the fact that the particular mechanism designed was expensive in its construction.

More particularly, it is the object of our invention to devise an interlocking bolt mechanism in which a pair of bolts are secured to a main bolt body which is pivoted at a relatively distant point from the overhanging portion of the casing. The pair of bolts will thus partake of a rocking motion with the main bolt body about this pivot, this rocking motion of the main bolt body being translated into a substantially vertical movement of the pair of bolts, due to the relatively distant pivot point of said main bolt body.

It is a further object of our invention to devise a simple inexpensive deadlocking mechanism in the form of a slide which is reciprocated for moving the rocking bolt body into its two extreme positions, and for deadlocking the same in those positions in a very simple manner.

It is a further object of our invention to devise a rollback bearing a particular relation to the lock operating mechanism, so that the normal positioning of the rollback will automatically deadlock the bolts and the lock operating mechanism. It is still a further object of the invention to devise an inside rollback which cooperates with a rollback operating spring and a cup-like member for maintaining the cup-like member in an operative position relatively to the outside rollback.

50 A further object of the invention is the design of a bolt mechanism which may be fabricated very cheaply.

It is a further object of our invention to so design the casing that it may be made of an integral die casting, with certain bearing portions inserted subsequent to the main die casting of the casing, in order to facilitate the casting of the main casing. It is still a further object of the invention to devise a casing cover which acts not only to maintain the bearing of the casing in its

inserted position, but cooperates with a stud on the main body of the casing, for at the same time maintaining the rocking bolt in an operative position.

As may be seen from the above rather long list of improvements resulting from our invention, this particular disclosure is the result of much study of this particular type of lock, and its conception is extremely valuable, as has been proven by the commercial success of this particular lock. 10 Therefore, while the particular modification will be described below in detail, it should be understood that relatively broad modifications of the particular described structure will be apparent to one skilled in the art, and we do not wish to be 15 limited to the details of this disclosure except as defined by the claims appended hereto.

For a more particular description of our invention, we shall now refer to the drawings, wherein Fig. 1 is a full front view of our lock and Fig. 2 is 20 a side view thereof. Fig. 3 is a view showing the back of the lock, while Figs. 4 and 5 are respectively front and side views of the strike with which the lock cooperates. Fig. 6 is a view of the lock with the back cover removed. Fig. 7 is a section 25 view showing the bolts in their locking position as demonstrated in Fig. 6. Fig. 8 is a sectional view of Fig. 6 showing the parts in their operative positions. Fig. 9 is a view similar to that of Fig. 6 and shows the bolts in an unlocking 30 position. Fig. 10 is a top and sectional view of the bolt body and the pair of interlocking bolts.

Fig. 11 shows two views of the bearing insert for the slide of the lock. Fig. 12 is a front and side view of the locking operating slide. Fig. 13 is a 35 front and sectional view of the inside rollback. Fig. 14 shows the spring which actuates the rollback. Fig. 15 is an elevation of a cup-like member utilized on the rollback for operating the rollback slide and for cooperation with the outside 40 rollback pin. Fig. 16 is a top view of Fig. 15 whereas Fig. 17 is a bottom view of Fig. 15. Figs. 18 and 19 illustrate the assembly of the cup-like member of Fig. 15, with the rollback of Fig. 13 and the spring of Fig. 14. 45

Referring now more particularly to the drawings, and especially Figs. 1 to 5 inclusive, it will be noted that our lock embodies a casing 10 having a rollback operating knob 11, a series of 50 screws 12 for securing the casing to a door, and an overhanging portion 13. A pair of bolt heads 14 are mounted in this overhanging portion and cooperate with ears 15 on a strike 16, in a manner which is well understood in the art. A rear casing cover 17 is secured by a screw 18 which is threaded into a stud 28 in the casing which will be described later. This rear casing cover 17 also carries a rollback mechanism 19 which cooperates with the usual tongue on the standard 55 60

cylinder (not shown) for operating the lock bolt as is understood by those skilled in the art.

The casing 10 is formed of die cast material, and in order to facilitate withdrawal of the rather complicated cores necessary to form the overhanging casing portion, we have arranged for the integral casting with the casing of bearing supporting portions 20 at opposite points on the casing. In these bearing supporting portions, we 10 mount the bearing 21 shown in Fig. 11, which is a die cast piece having the bearings lugs 22 which are adapted to guide the slide 23 of Fig. 12 in its bolt operating action.

The bolt heads 14, already described, are integral with a main bolt body portion 24 more particularly illustrated in Fig. 10. As will be noted, this bolt-body portion 24 is formed of a plate material which may be steel, brass, etc., and the cylindrical bolt portions 14 are formed integrally 20 with said main body portion by the curling or bending of the extensions, 24a as is quite obvious. In the usual practice, it is advisable to fill in the hollow portions formed in the cylindrical bolts 14, with lugs or other solid metal so as to present a 25 solid body. The bolt body 24 is formed with integral lugs 25 which act to guide the bolt by cooperating with the casing cover 17, and has a diagonal slot 26 which is adapted to cooperate with the pin 27 of the slide 23 for actuating the 30 bolt, as will be apparent later. The bolt 24 is also pierced at 27' for cooperation with a fixed stud 28 on the main body of the casing and is held in operative relation to the stud and to the lock casing by the screw 18, which, at the same time, 35 holds the rear cover 17 in position as has been described above.

As has been quite apparent already, the reciprocating movement of the operating slide 23 is adapted, through the coaction of the pin 27 with the slot 26 in the bolt body 24, to rock that bolt body about its pivot on the stud 28 and into the locking position of Fig. 6 or the unlocking position illustrated in Fig. 9. We shall now attempt to describe the means for operating the slide 23, and 45 for deadlocking the same at its extreme reciprocated positions; and for controlling this slide from the outside of the lock, or from the inside as may be the case.

The inside thumb turn 11 is mounted in the 50 casing 10 for rotary movement and has fixed thereon the rollback 29 shown more particularly in Fig. 13. This rollback carries a pin 30 which is grooved at 31 for a purpose to be described presently. Mounted on this pin 30 is a cup-like member, illustrated more particularly in Figs. 15 to 19 55 inclusive. This cup-like member has a cylindrical portion 33 flattened at two sides 33' which is adapted to operate in the slot 34 of the slide 23 for reciprocating the same as will be quite 60 readily understood.

The member 32 is cut out or slotted at 34, so 65 that the spring 35, detailed in Fig. 14, will rest in said cut-out portion and bear against the groove 31 of the stud 30. It is quite apparent that the spring 35 will function to maintain the rollback and its member 32, at the end of the slot 34 of the lock operating slide 23, and will also function through the cut-out portion 34 and the groove 31, to maintain the cup-like member 32 on the pin 30. This cup like member is also equipped with a relatively larger cylindrical portion 36' which is cut away at 36 for the admission of the pin 37 carried by the rollback 38 of the outside operating device 19, which has already

been described. It is readily understood that by this arrangement, the inside-rollback pin 30 or the outside rollback pin 37 will each be able to operate the slide 23 by means of the member 32.

The relation of the rollback 29 to pin 30, and 5 the cup-member 33, is such relatively to the slide 23, that when the spring 35 presses said rollback into its final position at the end of the slot 34, as shown more particularly in Figs. 6 and 9, the rollback pin 30 will be in dead center relation 10 relatively to the reciprocating movement of the slide 23 and will act to maintain the same deadlocked in either the position of Fig. 6 or the position of Fig. 9 so as to maintain the body bolt 24 15 in either of its two extreme positions.

It is thought that the above description clearly indicates the operation of a particular embodiment of our invention, the scope of the invention being indicated in the claims inserted below.

We claim:

1. In a lock, a casing having an overhanging strike interlocking portion, a pair of bolt heads in said portion secured to a common body portion for movement into interlocking relation with the strike, said body portion being pivoted at the other 25 extreme end of said casing, a slide in said casing, a rollback for operating said slide, and cooperating cam means on said slide and bolt body adapted to impart a pivotal movement to said body, said movement being translated into a substantially 30 vertical movement of said pair of bolt heads.

2. In a lock, a casing having an overhanging strike interlocking portion, a pair of bolt heads in said portion secured to a common body portion for movement into interlocking relation with the strike, said body portion being pivoted at a point relatively far removed from said overhanging portion, a slide in said casing, a rollback cam for operating said slide and for deadlocking the same in its extreme throw positions, and operating means between said cam and bolt body for moving the body on its pivot, and for deadlocking the same at its extreme throw positions with the pair of bolt heads in locking or unlocking position. 45

3. In a lock, an operating mechanism, a rollback adapted to operate said mechanism, said rollback having mounted thereon a cup-like member, a spring for pressing said rollback into a designated position, and cooperating portions of said rollback and cup-like member contacting with said spring whereby the spring maintains said member on said rollback while urging the rollback into its designated position. 50

4. In a lock, an operating mechanism, a rollback adapted to operate said mechanism, a pin on said rollback, a cup-like member mounted on said pin, a spring for pressing said rollback into a designated position, a slot in said cup-like member, said spring being adapted to bear on said rollback pin through said slot whereby to maintain said member on said pin while pressing the rollback into its designated position. 60

5. In a lock, in combination, a rollback having a pin, an operating member mounted on said pin, a portion of said member being cut away and exposing said pin, and a rollback operating spring adapted to bear on said pin through said member opening so as to retain said member on said pin while operating said rollback. 65
